58 Inventor:
Ralph A. Schoenberg.

UNITED STATES PATENT OFFICE.

RALPH A. SCHOENBERG, NOW BY JUDICIAL CHANGE OF NAME, RALPH A. BELMONT, OF NEW YORK, N. Y., ASSIGNOR TO BEAVER MACHINE AND TOOL CO., INC., OF NEWARK, NEW JERSEY, A CORPORATION OF NEW JERSEY.

PULL-SOCKET.

1,393,043.

Specification of Letters Patent. Patented Oct. 11, 1921.

Application filed April 28, 1916. Serial No. 94,141.

To all whom it may concern:

Be it known that I, RALPH A. SCHOENBERG, now by judicial change of name, RALPH A. BELMONT, of New York city, in the county 5 and State of New York, have invented a new and useful Pull-Socket, of which the following is a specification.

The main object of my invention is to improve and simplify pull sockets of the quick- 10 make and quick break type.

One feature of my invention consists in doing away with a number of springs heretofore used.

Another feature consists in a peculiar 15 spring which is arranged to give a quick snap.

Another feature is that both stationary contacts and the rotating shaft are on one member of the body.

20 Another feature is a double one piece spring held at its center by a shaft.

Another feature is a shaft provided with integral key ears and also insulated from the center of the rotary spring.

25 Other features will be pointed out below.

In the drawings:

Figure 1 is an elevation, partly in section, of a device embodying my invention;

Fig. 2 is a partial longitudinal sectional 30 view;

Fig. 3 is a section on line 3-3 of Fig. 2;

Fig. 4 is a section on line 4-4 of Fig. 2;

Fig. 5 is a section line 5-5 of Fig. 2, and

35 Fig. 6 is a sectional detail.

My improved pull chain socket comprises a body of porcelain or the like on or within 40 which the terminals and switch mechanism are mounted, said body being herein shown as confined within a metallic shell made up of two telescoping sections 1 and 2 secured together in any suitable fashion. As usual

I have provided the shell 1-2 with a lining 3 of fiber or other suitable non-conducting 45 material.

The porcelain body just referred to is herein shown as substantially cylindrical in form and as made up of two substantially semi-cylindrical sections 4 and 5 fastened 50 together by two screws 6 and 7, said sections being recessed at their lower ends to receive and interlock with the cross-bar 8 at the inner end of a screw shell contact 9

adapted to receive a lamp, attachment plug or the like.

55

The threaded end of the screw 6 engages the shank 10 of a center contact 11 adapted to engage the center contact of the lamp or the like, said shank being held by said screw within a recess 12 provided upon the 60 exterior of body section 4 and being provided with a binding screw 13 by means of which one of the lead wires of a circuit may be fastened to said shank.

The switch mechanism of my improved 65 socket comprises a rotating bridging contact 14 made from a single piece of spring metal and comprising two resilient arms 15, 15 connected by a cross-bar 16, the latter being fastened near its middle to the upper 70 end of a shaft 17 rotatably confined between the two sections of the porcelain body 4-5. As herein shown the upper end of shaft 17 is forked and the cross-bar is clamped between the tines of this fork with a jacket 75 18 of insulating material surrounding said bar and insulating it from the shaft.

The resilient arms 15 of the rotating bridging contact 14 cooperate with two stationary contacts 19 and 20 each of which is 80 curved eccentrically with relation to the axis of the rotating bridging contact 14 and disposed so that the lower end thereof, viz., the end of the stationary contact that is farthest from said axis, is first engaged by 85 one or the other of the resilient arms 15 when the bridging contact 14 is rotated in the direction of the arrow. At the opposite or highest end of each eccentrically curved stationary contact there is provided an 90 abrupt shoulder or step 21 and these two shoulders or steps prevent reverse movement of arms 15 and also provide for a quick and effective "break" when said arms ride off from the high ends of the stationary contacts. That is, these steps or shoulders 21 permit the resilient arms 15 to snap 95 radially outward away from contacts 19 and 20 as they leave the latter, it being clear that as the arms 15 traverse the contacts 19 and 20 they are deflected by the latter close in toward shaft 17 owing to the eccentricity of said contacts so that they are under more than normal stress or tension when they reach the high ends of contacts 19 and 20.

95

100 The bridging contact 14 and stationary

105

- contacts 19 and 20 are arranged within a chamber 22 provided within body 4—5 near the upper end thereof, and those portions of the side wall of said chamber located between 5 the end of contacts 19 and 20 which are engaged by arms 15 while the latter are traveling from one contact to the other, are preferably also eccentrically curved or disposed with relation to the axis of bridging contact 10 14 so as to provide steps or shoulders 23 adjacent the approach ends of contacts 19 and 20 off from which the arms 15 snap onto said contacts so as to provide a quick "make" as well as to prevent the bridging contact 14 15 being reversely rotated out of engagement with said contacts. Thus the steps or shoulders 21 provide for a quick "break" of the circuit and prevent the bridging contact being reversely rotated into engagement with 20 contacts 19 and 20, while steps or shoulders 23 provide for a quick "make" of the circuit and prevent the bridging contact being reversely rotated out of engagement with contacts 19 and 20.
- 25 Stationary contact 19 is made with a shank 24 disposed between the two body sections 4 and 5 and this shank is fastened to section 5 by a screw 25 which also fastens one end of a conductor 26 to said section. 30 The opposite end of conductor 26 is held in place on section 5 by screw 7 whose threaded end engages a binding screw plate 27 and holds the latter in place on the exterior of section 4. Plate 27 carries a binding screw 35 28 by means of which the other lead wire (not shown) may be secured to said plate. The other stationary contact 20 is made with a shank 29 extending lengthwise of the body between sections 4 and 5 and having its 40 lower end soldered or otherwise secured to the cross-bar 8 of screw shell 9. It will thus be clear that when the circuit is closed by the rotating bridging contact 14 it is traced from one lead wire through center contact 45 11 to one terminal of the device with which the socket is connected and from the other terminal of said device through screw shell 9, shank 29, contact 20, bridging contact 14, contact 19, shank 24, screw 25, conductor 26, 50 screw 7 and plate 27 to the other lead wire. From the chamber 22 the shaft 17 extends lengthwise of the socket through a second chamber 30 having at one side thereof an opening or passage 31 formed in section 5 55 and within which is secured a metallic guide tube or bell mouth 32 for a ball chain 33 which extends from the exterior of the socket through said tube into chamber 30 where its inner end is secured, as at 34 to a 60 chain supporting wheel or disk 35 that is loosely mounted upon shaft 17, so that it can oscillate freely relatively thereto. To this disk 35 is fastened one end of a spring 36 whose opposite end is anchored within the 65 joint between the two body sections 4 and 5 as indicated at 37. This spring 36 normally positions disk 35 so that the inner end of chain 33 partly encircles shaft 17 and by pulling upon the outer end of said chain the disk will be rotated in one direction and 70 when the pull on said chain is relieved the spring will rotate the disk in the opposite direction back to its normal position again. Between the disk 35 and the bottom wall 38 of chamber 30 is arranged a metallic washer 75 39 through which shaft 17 loosely extends and which provides a smooth seat for rotatably supporting disk 35.
- That portion of ball chain 33 which extends around shaft 17 is in engagement with 80 the periphery of a toothed ratchet wheel 40 that is keyed to said shaft by means of two integral fins 41 engaging notches 42 in wheel 40 and when the outer end of the chain is pulled upon the latter is drawn tightly 85 against ratchet wheel 40 and as it moves outward the engagement of its balls with the teeth of said wheel causes the latter to be rotated in the direction of the arrow, Fig. 4. When the chain is released the spring 36, acting 90 through disk 35, pulls the chain back into chamber 30 but at this time the chain is not under tension and therefore its balls slip idly past the teeth of ratchet wheel 40, the shoulders 21 preventing backward movement 95 of the ratchet wheel. The parts are so constructed and arranged that each time the chain is pulled outwardly to the limit of its movement shaft 17 is moved one quarter of a revolution and it will therefore be clear 100 that alternate step movements of shaft 17 will bring contact 14 into circuit closing position and the other step movements into circuit opening position.
- The shaft 43 carrying bridging contact 14 105 is mounted entirely within sockets 43 provided upon the inner face of section 5, the inner face of section 4 extending across these sockets as indicated in Fig. 4 so as to hold said shaft within the latter. As pointed 110 out above both stationary contacts 19 and 20 are also mounted upon the body section 5 and it will therefore be clear that all of the parts of the switch mechanism being thus mounted on one section of the body can all 115 be assembled in exact and proper relation on said section before the latter is secured to the opposite section 4 which is a feature of practical importance because it insures the parts occupying proper relative positions 120 after assembly.
- What I claim is:
1. A device of the character described comprising a circuit-controlling switch including a shaft and a radially resilient contact; a ratchet wheel connected with said shaft so that the wheel and shaft rotate together; a pull chain extending around said ratchet wheel and in engagement with the teeth of said wheel when the chain is moved 130

in one direction; a retracting spring operatively connected with the inner end of said chain; and means for preventing reverse movement of the wheel and shaft during the movement of the chain under the influence of said spring.

2. A device of the character described comprising a body formed with an interior chamber; a circuit-controlling switch including a shaft extending into said chamber; a ratchet wheel within said chamber and loosely mounted on said shaft but connected to rotate therewith; a pull chain extending around said wheel and engaging the latter; a chain-supporting member within said chamber loosely mounted on said shaft and having the inner end of said chain connected therewith; and a spring in said chamber connected at one end with said member and at 20 its opposite end to said body, walls of said chamber serving to hold said wheel and member against movement endwise on said shaft.

3. A device of the character described comprising a body in two sections; two fixed contacts mounted on one of said sections; a shaft rotatably mounted on said section and extending longitudinally of the device; a radially resilient bridge contact 30 carried by said shaft and coöperating with said fixed contacts; a pull chain extending crosswise of the device; and means carried by said shaft and connected with said chain through which said shaft is actuated step by step through movement of the chain.

4. A device of the character described comprising a circuit-controlling switch including a body; a shaft; a radially resilient

contact carried by said shaft; a ratchet wheel connected with said shaft so that the wheel and shaft rotate together; a pull chain extending around said ratchet wheel and in engagement therewith when the chain is moved in one direction; a chain-supporting member loosely mounted on said shaft along side said wheel and having the inner end of said chain fastened thereto; a spring having one end thereof connected with said member and the other end connected with said body; and means for preventing reverse movement 50 of the wheel and shaft when said member and chain are moved reversely by the spring.

5. A device of the character described comprising a body; two fixed contacts mounted on said body; a shaft extending longitudinally of the device; a bridge member carried by said shaft and coöperating with the fixed contacts, said bridge member comprising a pair of radially resilient contact arms adapted near their outer ends to engage said fixed contacts and connected at their inner ends by a cross-bar that is connected near its middle to said shaft; a ratchet wheel mounted on and connected with said shaft so that said wheel and shaft rotate together; a pull chain extending around and in engagement with said wheel when the chain is moved in one direction; a chain supporting member loosely mounted on said shaft alongside of said wheel and having the inner end of said chain connected therewith, and a spring connected at one end with said member and at its opposite end to said body.

RALPH A. SCHOENBERG.
